CLAIM

The ornamental design for a display on head mounted display with graphical user interface, as shown and described.

DESCRIPTION

FIG. 1 is a front view of a graphical user interface for display on head mounted display;

FIG. 2 is a front view of another embodiment thereof in which the first circle of the five circles illustrated on the left side of the design is highlighted;

FIG. 3 is a front view of another embodiment thereof in which the second circle of the five circles illustrated on the left side of the design is highlighted;

FIG. 4 is a front view of another embodiment thereof in which the third circle of the five circles illustrated on the left side of the design is highlighted;

FIG. 5 is a front view of another embodiment thereof in which the fourth circle of the five circles illustrated on the left side of the design is highlighted; and,

FIG. 6 is a front view of another embodiment thereof in which the fifth circle of the five circles illustrated on the left side of the design is highlighted.

The four icons on the upper right corner of FIGS. 1-6 (i.e., the “3G” icon, the signal strength icon, the battery charge icon and the time icon of “11:20”) illustrate environmental subject matter only and form no part of the claimed design.
